UNITED STATES PATENT OFFICE.

COLIN ALLEN CUNNINGHAM, OF BRAINERD, MINNESOTA.

BACK-PRESSURE RELIEF-VALVE.

SPECIFICATION forming part of Letters Patent No. 780,866, dated January 24, 1905.

Application filed June 6, 1904. Serial No. 211,289.

To all whom it may concern:

Be it known that I, COLIN ALLEN CUNNINGHAM, a citizen of the United States, and a resident of Brainerd, in the county of Crow Wing and State of Minnesota, have invented a new and Improved Back-Pressure Relief-Valve, of which the following is a full, clear, and exact description.

The invention relates to locomotive steam-engines; and its object is to provide a new and improved back-pressure relief-valve arranged to completely relieve the piston in the steam-cylinder of all pressure over and above steam-chest pressure, thus insuring a steady running of the engine and utilization of the motive agent to the fullest advantage and relieving the piston of all pressure when the engine is drifting.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement as applied to one end of the engine-cylinder and steam-chest. Fig. 2 is a sectional plan view of the improvement on the line 2 2 of Fig. 1. Fig. 3 is a sectional side elevation of the improvement provided with a cushioning-valve in the outlet, and Fig. 4 is a sectional plan view of the same on the line 4 4 of Fig. 3.

On each end of the cylinder A of the locomotive steam-engine is externally secured an elbow B, on which is screwed or otherwise fastened a casing C, preferably made in three parts C¹, C², and C³, of which the upper part C¹ is closed by a screw-cap C⁴ and the lower part C³ is secured to the elbow B. The lower part C³ of the casing is provided with a valve-seat C⁵, on which is adapted to be seated the valve D' of a piston-valve D, having its piston D² fitted snugly in the upper part C¹ of the casing C, as plainly shown in Fig. 1. On the under side of the piston-valve D presses a

in an uppermost position with the valve D' off the seat C⁵ to establish communication between the interior of the cylinder A and the atmosphere by way of the elbow B, the seat C⁵, and the middle part C² of the casing, which middle part is provided with one or more ports or outlets C⁶, leading to the outer air. Thus when the engine is drifting at the time the locomotive, say, is running down a hill, then the piston in the cylinder A is prevented from pumping and compressing air, as each end of the cylinder is open to the atmosphere by way of the relief-valve, as described.

The cap C⁴ of the casing C is connected by a pipe F with the interior of the steam-chest G, so that the steam-chest pressure is on the top of the piston-valve D, and consequently presses the piston-valve D downward, so as to hold the valve D' on its seat while the engine is running; but when the piston in the cylinder A nears its end stroke and creates a pressure above that in the steam-chest G then this preponderance of pressure acts on the under side of the valve D' to lift the piston-valve, so as to open the valve-seat C⁵ to allow the preponderance of pressure to pass to the atmosphere by way of the open valve-seat C⁵ and the outlets C⁶. As soon as the pressure in the cylinder A is reduced to that of the live-steam pressure in the steam-chest G then the piston-valve is again forced downward and the valve D' moves to its seat C⁵ and the spring E is compressed.

If desired, a cushioning-valve H may be employed, and in this case the valve-casing H' of the cushioning-valve H is provided with a single outlet C⁷, registering with the space between the valve D' and the piston D² of the piston-valve D. The valve-casing H' is provided with a valve-seat H², on which is seated an outwardly-opening valve H³, normally held to its seat by a spring H⁴, arranged in the valve-casing H', opening with its outer end to the atmosphere. It is understood that when the valve D' is pushed off its seat by back pressure in the cylinder, then this back pressure has to overcome the valve H³ before it can pass to the outer air; but in order to prevent a vacuum being formed in the part C² at the time the engine is drifting and the

valve D' is held off its seat by the action of the spring E, I provide the valve H³ with a central port H⁵, leading to the outer air, so that air can pass into the part C² of the casing 5 even when the valve H³ is closed.

It is understood that when the steam is shut off from the engine the spring E immediately pushes the piston-valve D upward to move the valve D' off its seat and to hold it off its seat until steam is again admitted to the steam-chest. By the arrangement described the piston-valve D is prevented from flopping, and a direct connection is had from the cylinder to the atmosphere. By the use of the cushioning-valve 15 H the piston is prevented from pumping much air into the cylinder, and by having the port H⁵ in the said valve a vacuum is avoided in the part C², and the piston-valve D is hence prevented from being drawn to its seat. The 20 tension of the spring E is such as to compensate for the increase in area of the piston D² over the valve D', so that the piston-valve is moved upward by the spring E and the valve D' is moved off its seat C⁵ as soon as the pressure in the cylinder rises above that in the steam-chest G.

Having thus described my invention, I claim as new and desire to secure by Letters Patent—

1. A back-pressure relief-valve, comprising 30 a casing connected at one end with the interior of the steam-cylinder and at the other end with the steam-chest, the casing having a valve-seat at the end connected with the steam-cylinder and an outlet intermediate of its ends, 35 said outlet leading to the atmosphere, and a piston-valve in the said casing, the valve of the piston-valve being adapted to be seated on the valve-seat and the piston being of a larger area than the piston-valve, and means for holding 40 the valve from its seat when the piston is relieved of steam-chest pressure, whereby the cylinder is placed in communication with the atmosphere when the engine is drifting.

2. A back-pressure relief-valve, comprising 45 a casing connected at one end with the interior of the steam-cylinder and at the other end with the steam-chest, the casing having a valve-seat for connection with the steam-cylinder and an outlet leading to the atmosphere, a pis-

ton-valve in the said casing, the valve of the 50 piston-valve being adapted to be seated on the valve-seat and the piston being of a larger area than the piston-valve, and the said outlet being intermediate the piston and the valve when the latter is seated and the pressure from 55 the steam-chest is on the piston, and a spring pressing the piston-valve to move and hold the valve off its seat when the piston is relieved of steam-chest pressure.

3. A back-pressure relief-valve, comprising 60 a casing connected at one end with the interior of the steam-cylinder and at the other end with the steam-chest, the casing having a valve-seat for connection with the steam-cylinder and an outlet leading to the atmosphere, a piston-valve in the said casing, the valve of the 65 piston-valve being adapted to be seated on the valve-seat and the piston being of a larger area than the piston-valve and the said outlet being intermediate the piston and the valve 70 when the latter is seated and the pressure from the steam-chest is on the piston, a spring pressing the piston-valve to move the valve off its seat, and a cushioning-valve in the said outlet.

4. A back-pressure relief-valve, comprising 75 a casing connected at one end with the interior of the steam-cylinder and at the other end with the steam-chest, the casing having a valve-seat for connection with the steam-cylinder 80 and an outlet leading to the atmosphere, a piston-valve in the said casing, the valve of the piston-valve being adapted to be seated on the valve-seat and the piston being of a larger area than the piston-valve and the said outlet 85 being intermediate the piston and the valve when the latter is seated and the pressure from the steam-chest is on the piston, a spring pressing the piston-valve to move the valve off its seat, and a cushioning-valve in the said outlet, 90 having a central port open at all times.

In testimony whereof I have signed my name to this specification in the presence of two subscribing witnesses.

COLIN ALLEN CUNNINGHAM.
